(57) **CLAIM**

(21) Appl. No.: **29/158,319**

The ornamental design for a lockable electronic timer and limiter, as shown and described.

(22) Filed: **Apr. 4, 2002**

DESCRIPTION

(51) LOC (7) Cl. **10-03**

FIG. 1 is a top view of a lockable electronic timer and limiter with cover open showing my new design.

(52) U.S. Cl. **D10/40**

FIG. 2 is a bottom view of the lockable electronic timer and limiter with cover open.

(58) Field of Search .... D10/1-40, 122-132; 368/96-100, 107-121, 276-277, 285, 316, 317, 10; 200/38.12, 80; 307/141 R, 141.1

FIG. 3 is a side view of the lockable electronic timer and limiter with cover open.

(56) **References Cited**

FIG. 4 is another side view of the lockable electronic timer and limiter with cover open.

U.S. PATENT DOCUMENTS

FIG. 5 is a front end view of the lockable electronic timer and limiter with cover open.
